US0D1088715S

(12) **United States Design Patent** (10) Patent No.: **US D1,088,715 S**
(45) Date of Patent: ** Aug. 19, 2025

(54) **BOTTLE LID**

(71) Applicant: **U.I.E INTERNATIONAL LIMITED**,
Wan Chai (HK)

(72) Inventor: **Jin Huang**, Beijing (CN)

(73) Assignee: **U.I.E INTERNATIONAL LIMITED**,
Wan Chai (CN)

(**) Term: **15 Years**

(21) Appl. No.: **29/997,244**

(22) Filed: **Apr. 7, 2025**

(51) LOC (15) Cl. **07-02**

(52) U.S. Cl.

USPC **D7/392.1**

(57) **CLAIM**

The ornamental design for a bottle lid as shown and described.

DESCRIPTION

FIG. 1 is a front, left and top perspective view of a bottle lid, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, left and top perspective view of the bottle lid of FIG. 1 shown in another configuration of use. The dashed broken lines depict portions of the bottle lid that form no part of the claimed design.

1 Claim, 9 Drawing Sheets
